(57) **CLAIM**

We claim the ornamental design for a television receiver for an automobile, as shown and described.

DESCRIPTION

FIG. 1 is a front view of a television receiver for an automobile of the present invention, wherein the television receiver is in an open position;

FIG. 2 is a first side view thereof;

FIG. 3 is a second side view thereof;

FIG. 4 is a top view thereof;

FIG. 5 is a bottom view thereof;

FIG. 6 is a top perspective view thereof; and,

FIG. 7 is a top perspective view of the television receiver for an automobile of the present invention, wherein the television receiver is in a closed position.

The rear view has been omitted and forms no part of the claimed design.
